UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 655,647, dated August 7, 1900.

Application filed February 6, 1900. Serial No. 4,221. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

This invention relates to weft or filling changing or supplying mechanism for looms, and comprehends improvements in the magazine and in mechanical means controlled by the presence or absence of weft or filling in the weft-carrier and including a feeler and indicator for setting in motion at proper times the weft-supplying mechanism.

In the accompanying drawings, which illustrate an embodiment of the invention, Figure 1 is a side elevation of a part of the loom, showing the lay in its beat-up position in full lines and in its retracted position at the picking-point in dotted lines. Fig. 2 is a view showing the principal parts seen in Fig. 1, but on a larger scale and in a different position. Fig. 3 is a plan, and Fig. 4 a front elevation, of the feeler devices and the mechanism connected therewith for operating them. Fig. 5 is a vertical axial section of the shuttle, with the bobbin and bobbin-case in place therein. Fig. 6 is an under side view of the same, and Fig. 7 is a cross-section at A A in Fig. 5. Fig. 8 illustrates the application of a part of the invention to a shuttle wherein the bobbin-case is omitted, and Fig. 9 is a cross-section of the same at B B. Fig. 10 is a plan view of the magazine on the same scale as Fig. 1. Fig. 11 is a cross-section of the magazine on the same scale as Fig. 2.

Referring to the principal views, *a* is the loom-frame. *b* is the breast-beam, forming a part thereof. *c* is the vibratable lay carrying the reed and the shuttle-boxes, and *d* is the picker-stick. These parts are common in looms, and the moving parts may be actuated by the usual or any satisfactory mechanism.

In the loom-frame is mounted a supplying carrier or magazine *e*, adapted to be rotated intermittently up to a detent or stop *f* by a slip-belt *g* or other suitable means. When the lay *c* beats up, the shuttle-box *h* thereon

at one side of the loom is brought directly under the delivery-point of the magazine *e*, and when the weft or filling in the shuttle in play in said box is substantially exhausted such exhaustion of the weft or filling will set 55 in position intermediate mechanism, whereby a dagger or tappet carried by the lay or other going part will actuate a driver to drive a bobbin-case or bobbin in the magazine down into the shuttle, the impact of the incoming bobbin-case serving to displace the exhausted case in the shuttle and force it down through the latter and out below.

The supplying carrier or magazine will be particularly described hereinafter, and we 65 will now describe the feeler and indicator and their operating mechanism.

On the lay *c*, at the side of the shuttle-box *h*, is mounted a feeler-lever *i*, adapted to swing about a pivotal point *j*, and below, on 70 the side of the lay, is mounted a rock-shaft *k*, having an upright arm or prong *l*, which engages an aperture in said feeler-lever, whereby when the latter is moved to and fro the shaft *k* will be rocked. The free end of the feeler-lever *i* is adapted to play through a slot or aperture *m* in the side of the shuttle-box *h* and also to enter a shuttle *n*, which may be in the box, as will be hereinafter more fully explained. On the rock-shaft *k* is a 80 spring *o*, which tends at all times to press the feeler-lever inward toward the shuttle and into it. Also on the shaft *k* there is a tappet-arm *p*, which when the lay recedes to the picking and shuttle-receiving point is 85 caused to impinge upon a dagger or tappet *q* on the loom-frame, Fig. 1, in such a manner as to rock the shaft *k* and withdraw the feeler-lever *i* from the shuttle and box. The purpose of this withdrawing device is to free the 90 shuttle and box from the feeler devices, so as to leave the shuttle unencumbered and free to be picked and to leave the box unencumbered to receive the shuttle from the other side of the loom, as the case may be. 95 As shown herein, the dagger *q* plays through an aperture *r* in the lay *c* at a point therein where it will not impede the movement of the picker-stick in picking. The rock-shaft *k* has at its under side lugs *s*, in which is piv- 100

totally mounted a tappet *t*, supported by a blade-spring *u* to avoid too much rigidity.

The construction of the shuttle and the bobbin therein will now be described with especial reference to Figs. 5 and 6. In the side of the shuttle *n*, at or near its lower edge, is formed an elongated aperture, and in this aperture is pivotally mounted or fulcrumed a feeler-finger *v* with unequal arms. A spring *w* on the shuttle bears on the shorter arm or heel of the feeler-finger and tends to hold the latter normally alined with the side of the shuttle, as seen in Fig. 6. On the longer arm of this feeler-finger the feeler-lever *i* impinges in such a manner as to turn the finger about its pivot or fulcrum and cause its longer arm to sweep across the lower part of the shuttle. Normally when the lay is beating up and free from the dagger *q* the spring *o* rocks the shaft *k* in a manner to cause the feeler-lever *i* to press the feeler-finger *v* inward to its fullest extent, as indicated by the dotted line in Fig. 6, and to also elevate the tappet *p*, as seen in full lines in Fig. 1. The magazine *e* is supported on suitable brackets *x* on the loom-frame, and on the loom-frame is fulcrumed an elbow-lever, one arm of which forms the driver *y*, and the other arm *z* is so formed as to be impinged upon at the proper time by the tappet *t* for actuating the driver *y*. The manner of operation of the feeler *i* to rock the shaft *k* and place the tappet *t* in position to operate the driver when the lay beats up will be best understood after the construction of the bobbin in the shuttle shall have been explained. The bobbin 1 is mounted in a bobbin-case 2; and this bobbin-case is held in place in the hollow of the shuttle by spring-jaws 3. There will be a pair of these jaws, by preference, to embrace each end of the bobbin-case. The manner of mounting the bobbin in the bobbin-case and of mounting the said case in the shuttle is shown and described in our pending application, Serial No. 411, filed January 5, 1900. It will only be necessary to say here that the bobbin may be held in place in the bobbin-case by spring-jaws in all respects similar to the jaws 3 for holding in place the bobbin-case. We may say here also that by "bobbin" as the word is herein employed is meant any suitable form of known weft-holder. In the lower side of the hollow or tubular bobbin at its enlarged end is formed a longitudinal slot and in this slot is fulcrumed at 4 a lever-indicator 5, backed by a spring 6, which tends to press the indicator outward and downward radially. The indicator is so curved outwardly that when pressed out to its full extent by the spring 6 it will project into the path of the feeler-finger *v* in the shuttle; but normally the indicator will be overwrapped by the weft or filling on the bobbin, Fig. 3, and be thus held pressed back into the slot. Now assuming the bobbin in the shuttle in play to be supplied with weft and the loom in operation, when the shuttle enters the box *h*

at the picking-point the feeler-lever *i* will be pressed back through the medium of the dagger or tappet *q* and the spring *w*, Fig. 6, will be free to hold the feeler-finger *v* back in line with the side of the shuttle. As the lay beats up, and thus withdraws from the dagger *q*, the spring *o* rocks the shaft *k* and the latter acts on the feeler-lever *i* to swing the feeler-finger *v* across the shuttle underneath the bobbin; but in the course of the weaving the filling in the shuttle in play will become substantially exhausted, and thus clear or free the lever-indicator 5 of the bobbin, so that its spring 6 may press it outward or downward, as seen in Fig. 5. When the shuttle thus exhausted enters the shuttle-box *h* at the picking-point and the lay advances in beating up, the feeler-lever can only press in the feeler-finger until the latter impinges upon the protruding indicator 5, which it now finds in its path. Thus the shaft *k* will be rocked and the tappet *t* will be put into alinement with the arm *z* of the driver *y*, and as the lay moves up toward the beat-up position the tappet *t* will impinge on said arm *z*. The first effect of this will be to rock the shaft *k* until the lugs *s* come to a firm bearing on the face of the lay, and incidentally the feeler-lever *i* will be withdrawn, so as to permit the feeler-finger *v* to free itself from the bobbin and bobbin-case and return to its normal position in the recess at the side of the shuttle. The second and final effect will be to operate the driver *y* forcibly and suddenly at the moment the shuttle in the box takes a position directly under the delivery-point of the magazine, so that a bobbin-case will be driven from the magazine down into the shuttle, said case displacing and knocking out the one in the shuttle. This is the position of the parts seen in Fig. 2.

The spring *u* permits of the necessary movement of the tappet *t* about its pivot-point in the lugs *s* after the engagement of said tappet with the arm of the driver and during the subsequent rocking of the shaft *k* necessary to withdraw the feeler-lever *i* before the changing of the bobbin-cases. (See Fig. 2.)

In the principal views the invention is shown as employed in connection with a bobbin mounted in a bobbin case or box; but it may be employed as well where the bobbin is mounted directly in the shuttle. For example, Figs. 8 and 9 show the bobbin held in place in a self-threading shuttle *n'* by spring-jaws 3^a in a known way. It will be understood that where a bobbin-case is employed this case will be fed into the shuttle from the magazine and that the same will be the case where the bobbins alone are changed.

The indicator 5 may be provided with a heel or shorter arm 5^a back of the fulcrum, which heel projects into the hollow of the empty bobbin. The reasons for this construction are fully explained in our said pending application, Serial No. 411, and they need not be repeated here. It will suffice to say

that the feature is not claimed herein nor is the present application limited to the use of this feature.

We will now describe the device *e*, which for convenience we have called the "magazine," directing especial attention to Figs. 1, 2, 10, and 11. Two pairs of sprocket-wheels 8 and 8^a are mounted on spindles 9, fixed in the brackets or bracket-frames *x* on the loom-frame. The sprocket-wheels of each pair are conveniently connected by a hollow axle or boss, and on the pair 8 is a sheave 10, over which passes the slipping belt *g*. This belt is driven from a sheave 11 on the crank-schaft 12 of the loom, and it tends constantly to drive the pair of sprocket-wheels 8 in the direction indicated by the arrow thereat in Fig. 1. On the sprocket-wheels is mounted an endless-chain carrier comprising two chain 13, connected transversely by hinging-rods 14 where the links of the chains are jointed together. This chain carrier is driven through the medium of the sprocket-wheels 8 and drives the carrying sprocket-wheels 8^a. The endless carrier is here represented as moving horizontally from one pair of sprocket-wheels to the other, and this is the preferred arrangement. The lower side of the endless carrier is supported and kept properly alined by fixed guides 15, which are supported or may be supported from the bracket-frames which carry the wheels. The bobbin-cases 2 are mounted in the endless carrier, being held in place by suitable spring-clips 16, fixed to the links of the chain. As herein shown, the clip 16 is composed of two curved spring-fingers which take about the bobbin-case and hold it in place with sufficient firmness to prevent it from falling out. There is a clip on each link of the chain, the magazine when full carrying as many bobbin-cases as the endless carrier has pairs of links, and the driver *y* is by preference placed midway between the pairs of sprocket-wheels. Obviously when the driver *y* drives a bobbin-case 2 from the carrier down into the shuttle below, which latter will be directly beneath the driver in its beat-up position, the carrier will be moved along until the next bobbin-case of the series comes to impinge on the detent.

We are the first, as we believe, to have invented an endless-chain magazine or carrier for weft-holders or bobbin-cases containing weft-holders and means for supplying the same as needed to an active shuttle in the shuttle-box, and we therefore claim this feature broadly without limitation to specific means for accomplishing the result. Heretofore also, so far as we are aware, all feeler devices which are adapted to enter the shuttle-box have been positively actuated to move in and out at predetermined times. The novel feature of our feeler device lies in non-positive means—as a spring, for example—which tends to move the feeler-lever into the shuttle and box normally or at all times and positive means for withdrawing said feeler-lever

periodically to permit the shuttle to enter and leave the box. Being the first, as we believe, to employ such a device, we claim the same broadly and do not restrict ourselves to any specific devices for effecting the result.

Other known devices for setting in operation the supplying mechanism when the weft or filling in the shuttle is nearly or quite exhausted may be employed in lieu of that herein shown—as, for example, the electrical exhaustion-indicating mechanism illustrated in our pending application, Serial No. 411, filed January 5, 1900.

While we have shown herein bobbin-cases containing bobbins supported in the clips or springs of the endless-chain carrier, it will be obvious that the bobbin itself—such as that illustrated in Figs. 8 and 9, for example—may be supported in the chain, in which case a self-threading shuttle like that seen in Fig. 8 would be employed.

We have not deemed it necessary to illustrate herein a holder for the weft ends in connection with the magazine. Such holders are known, and any known form of weft-end holder may be employed—as, for example, that illustrated in our pending application, Serial No. 9,493, filed March 21, 1900.

By the phrase "weft-holder" as herein employed is meant any form of holder for weft or filling adapted to go into a shuttle or carrier, such as a bobbin-case containing weft, a bobbin, a cop, a butt-cop, or the like.

The embodiment of the invention herein illustrated does not contemplate supplying full shuttles, but supplying filling to a shuttle in play.

Having thus described our invention, we claim—

1. In a loom, the combination with a weft or filling supplying mechanism, a going part of the loom, and intermediate mechanism between said going part and supplying mechanism whereby the former is connected with the latter for operating it, of a shuttle having in it a spring feeler-finger adapted to swing transversely thereof when actuated by said intermediate mechanism, and a bobbin in said shuttle provided with a radially-movable indicator, backed by a spring which tends to move it into the path of said feeler-finger and held out of said path by the overwrapped weft or filling.

2. In a loom, the combination with a weft or filling supplying mechanism, a going part of the loom, and an intermediate mechanism between said going part and supplying mechanism whereby the former is caused to operate the latter at proper times, said intermediate mechanism being mounted on the going part adjacent to the shuttle-box and comprising a rock-shaft carrying an operating-tappet, a feeler-lever operated by said rock-shaft, and a spring tending to press said feeler-lever into the shuttle-box and into the shuttle therein, of a dagger on the loom-frame which withdraws said feeler-lever at the pick-

ing-point, and a shuttle carrying a weft-holder provided with a radially-movable indicator which tends to move outward into the path of the feeler device and which is held out of said path by the overwrapped weft or filling.

3. In a weft or filling supplying mechanism for looms, the combination with a shuttle having a spring feeler-finger adapted to swing across the shuttle, of a weft-holder having a radially-movable spring-indicator adapted to be moved into the path of said finger and to be held out of said path by the overwrapped weft, and means for holding said weft-holder in place in the shuttle.

15 4. In a weft or filling supplying mechanism for looms, the combination with a shuttle having a spring feeler-finger adapted to swing across the shuttle, of a weft-holder having a radially-movable spring-indicator adapted to be moved into the path of said finger and to be held out of said path by the overwrapped weft, a bobbin-case inclosing said weft-holder, and means for holding said bobbin-case in place in the shuttle.

25 5. In a weft or filling supplying mechanism for looms, the combination with a shuttle having a spring feeler-finger adapted to swing across the shuttle, of a weft-holder having a radially-movable spring-indicator adapted to be moved into the path of said finger and to be held out of said path by the overwrapped weft, a feeler-lever carried by the lay and adapted to normally press the feeler-finger into the shuttle in the shuttle-box, and means adapted to free the shuttle from said feeler-lever at the picking-point.

40 6. In a weft or filling supplying mechanism for looms, the combination with a shuttle having a spring feeler-finger adapted to swing across the shuttle, of a weft-holder having a radially-movable spring-indicator adapted to be moved into the path of said finger and to be held out of said path by the overwrapped weft, a feeler-lever carried by the lay and adapted to normally press the feeler-finger into the shuttle, and a dagger or tappet on the loom adapted to press back said feeler-lever at the picking-point.

50 7. In a weft or filling supplying mechanism for looms, the combination with a shuttle having a spring feeler-finger adapted to swing across the shuttle, of a weft-holder having a radially-movable spring-indicator adapted to be moved into the path of said finger and to be held out of said path by the overwrapped weft, a feeler-lever carried by the lay and adapted to normally press the feeler-finger into the shuttle, means for pressing back the feeler-lever at the picking-point, a driver for driving a weft-holder from the magazine, mechanism between the feeler-lever and the said driver for operating the latter, and the said magazine.

65 8. In a weft or filling supplying mechanism for looms, the combination with a magazine for supplying filled weft-holders, and means for actuating said magazine, of a driver for

driving the weft-holders from the magazine into the shuttle, the rock-shaft *k* on the lay, its spring, the tappet *t* on said shaft adapted to actuate said driver at proper times, the spring controlling said tappet whereby it may yield, the feeler-lever *i*, pivotally mounted on the lay and connected to the said rock-shaft for mutual operation, and means for rocking the shaft *k* at the picking-point to withdraw the feeler-lever from the shuttle.

9. In a weft or filling supplying mechanism, the combination with the driver having an arm *z*, of the rock-shaft *k*, on the lay, its spring, the tappet *t*, hinged thereon, the tappet-spring *u*, and the feeler-lever *i*, coupled to the rock-shaft for mutual operation.

10. In a weft-supplying mechanism, the combination with the magazine, or device for carrying the weft-holders, said magazine comprising endless chains, rotative supporting sprocket-wheels, and spring devices on the chains for supporting the weft-holders, of means for actuating said chain-carrier to bring the weft-holders successively to the delivery-point, supports for the chains at said point and a driver with a laterally-extending head which enters at the side and which is adapted to drive the weft-holder from the chain into the shuttle.

11. In a weft-supplying mechanism, the combination with a magazine, or device for carrying the weft-holders, said magazine comprising supporting sprocket-wheels and carrying-chains, which latter move in a substantially-horizontal plane and are provided with spring devices to support the weft-holders, supports for the chain at the delivery-point, means for actuating said magazine, a fixed 105 detent for arresting the movement of the magazine, and a driver situated above the lower side of the carrying-chains and adapted to drive the weft-holders down into the shuttle in the box below.

110 12. In a weft-supplying mechanism, the combination to form a magazine, or device for carrying the weft-holders, of the pairs of sprocket-wheels, rotatively mounted on the loom, the connected endless chains, the spring-clips on the links, and the supports 115 for the chains.

13. In a weft-supplying mechanism, the combination to form a magazine, or device for carrying the weft-holders, of the pairs of sprocket-wheels, rotatively mounted on the loom, the connected endless chains, the spring-clips on the links adapted to embrace the weft-holders and opening outward, means tending constantly to drive said magazine, a 125 fixed detent which normally arrests the movement of the magazine, and the supports for the said chains at the delivery-point.

14. In a weft or filling supplying mechanism for looms, the combination with a shuttle having a feeler-finger, and a weft-holder therein having an exhaustion-indicating device which controls the extent of movement inward of said finger, of spring-actuated means

- on the lay tending normally to move said finger into the shuttle, and means which periodically withdraws said device and permits said feeler-finger to withdraw.
- 5 15. In a weft or filling supplying mechanism, the combination with a magazine containing a reserve supply of weft, and means for transferring weft from said magazine to the shuttle in play as required, of a shuttle 10 having a feeler-finger, a weft-holder in the shuttle having an exhaustion-indicating device which controls the extent of movement inward of said finger, spring-actuated mechanism on the lay tending normally to press 15 said feeler-finger into the shuttle, and means which periodically withdraws said pressing mechanism to permit the shuttle to enter and leave the shuttle-box.
16. In a weft or filling supplying mechanism, the combination with a magazine containing 20 a reserve supply of weft, said magazine consisting of an endless-chain carrier provided with means for supporting the weft-holders, and means for transferring weft from 25 said magazine to the shuttle in play as required, of a shuttle having a feeler-finger, a weft-holder in the shuttle having an exhaustion-indicating device which controls the extent of movement inward of said finger, 30 spring-actuated mechanism on the lay tending normally to press said feeler-finger into the shuttle, and means which periodically withdraws said pressing mechanism to permit the shuttle to enter and leave the shuttle- 35 box.
17. In a loom, a weft or filling replenishing mechanism comprising a magazine or holder for a reserve supply of weft or filling, said holder consisting of an endless-chain carrier 40 furnished with means for supporting the weft-holders therein, means for effecting the transfer of a weft-holder from said magazine to the shuttle in play, and exhaustion-indicating devices controlling the operation of 45 said transferring mechanism, said indicating devices comprising a weft-exhaustion indicator in the weft-holder, a feeler-finger in the shuttle, controlled by the exhaustion-indicator, and a feeler-lever which coöperates 50 with said feeler-finger.
18. In a loom, a weft or filling replenishing mechanism comprising a magazine or holder for weft-holders containing a reserve supply of weft or filling, said holder consisting of an 55 endless-chain carrier furnished with means for supporting the weft-holders therein, means for effecting the transfer of a weft-holder from said magazine to the shuttle in play, a slip-belt, tending constantly to move 60 said magazine, a detent which arrests said movement, supports for the carrier at the delivery-point, and exhaustion-indicating devices controlling the operation of said transferring mechanism.
- 65 19. In a loom, a weft or filling replenishing mechanism comprising a magazine or holder for bobbin-cases containing a reserve supply of weft or filling, said holder consisting of an endless-chain carrier furnished with means for supporting the weft-holders therein, means for effecting the transfer of a weft-holder from said magazine to the shuttle in play, a slip-belt, tending constantly to move 70 said magazine, a detent which arrests said movement, supports for the carrier at the delivery-point, and exhaustion-indicating devices controlling the operation of said transferring mechanism, said devices comprising a weft-exhaustion indicator in the weft-holder, a feeler-finger in the shuttle, controlled by the exhaustion-indicator, and a feeler-lever which coöperates with said feeler-finger.
20. In a loom, a weft or filling replenishing mechanism comprising a magazine for weft-holders containing a reserve supply of weft or filling, said magazine consisting of an endless-chain carrier provided with means for supporting the weft-holders therein, a support for the carrier situated between the latter and the shuttle-box at the delivery-point, means for effecting the delivery of the weft-holder from the magazine to the shuttle in play, and exhaustion-indicating devices made 85 operative and inoperative by the shuttle in play for controlling the operation of said transferring mechanism.
21. In a loom, a weft or filling replenishing mechanism comprising a magazine for weft-holders containing a reserve supply of weft or filling, said magazine consisting of an endless-chain carrier provided with means for supporting the weft-holders therein, a support for the carrier situated between the latter and the shuttle-box at the delivery-point, means for actuating said carrier to bring the weft-holders successively to the delivery-point, a driver adapted to drive the weft-holders from the chain into the shuttle, and 90 exhaustion-indicating devices controlling the times of operation of said supplying mechanism.
22. A movable feeder and magazine for weft-holders, consisting of an endless-chain carrier having a series of yielding supports to receive and hold said weft-holders, and situated between the chain and the shuttle-box, a support to steady the said weft-holders while they are being transferred, substantially as 100 set forth.
23. The combination with a rotatable magazine and feeder for weft-holders, consisting of an endless chain having spring devices for supporting a series of said weft-holders, and situated between the chain and the shuttle-box, a support to steady the said weft-holders while they are being transferred, of a stop device against which bears the weft-holder next to be removed from said magazine, substantially as set forth.
24. In a loom for automatically supplying a shuttle with a full weft-holder, the combination with a rotatable magazine and feeder for weft-holders, said magazine consisting of an endless chain provided with devices for supporting a series of weft-holders, and situated between the chain and the shuttle-box, a support to steady the said weft-holders.

while they are being transferred, and means for rotating or driving said magazine at proper times to bring a fresh weft-holder to the delivery-point, and a driver adapted to 5 drive the weft-holder from its supports into the shuttle, substantially as set forth.

25. A movable magazine and feeder for weft-holders, the same consisting of an endless chain having devices for supporting a 10 plurality of weft-holders, and situated between the chain and the shuttle-box, a support to steady the said weft-holders while they are being transferred, means for moving said magazine at the proper time to bring a weft- 15 holder therein to the proper point for delivery, and a restraining device which arrests the movement of said magazine while the weft-holder is being transferred, in combination with a driver for ejecting the weft- 20 holder from the machine, substantially as set forth.

26. A loom having the following instrumentalities, namely: a shuttle-box, a shuttle open for the passage through it of a weft-

holder, a driver or pusher, a magazine and 25 feeder for weft-holders, the same consisting of a movable, endless chain having devices for supporting a plurality of weft-holders, and situated between the chain and the shuttle-box, a support to steady the said weft-holders while they are being transferred, mechanism for intermittently moving said magazine to bring the weft-holders therein in 30 succession into position for transfer from the magazine to the shuttle, and mechanism for 35 actuating said driver to transfer said weft-holders, one by one, as required, from the magazine to the shuttle in the shuttle-box, substantially as set forth.

In witness whereof we have hereunto signed 40 our names, this 29th day of January, 1900, in the presence of two subscribing witnesses.

WILLIAM H. BAKER.
FREDERIC E. KIP.
